UNITED STATES PATENT OFFICE

140,425

DESIGN FOR A MAILBOX

Walfred Johnson, Racine, Wis.

Application November 21, 1944, Serial No. 116,463

Term of patent 14 years

(Cl. D74—9)

To all whom it may concern:

Be it known that I, Walfred Johnson, a citizen of the United States, residing at Racine, in the county of Racine and State of Wisconsin, have invented a new, original, and ornamental Design for a Mailbox, of which the following is a specification, reference being had to the accompanying drawing, forming part thereof.

The figure is a perspective view of a mailbox showing my new design, the back, the top and the end not shown, being plain.

I claim:

The ornamental design for a mailbox, as shown and described.

WALFRED JOHNSON.
